Attorneys

UNITED STATES PATENT OFFICE

WILLIAM ALFRED BARDEN, OF NEW YORK, N. Y.

GROUND-GRIPPING DEVICE FOR SHOES

Application filed July 10, 1931. Serial No. 549,984.

This invention has to do with ground-gripping devices for shoes. Though particularly designed for use by golf players, it may, of course, be utilized wherever it is necessary or desirable to equip shoes with ground-gripping means.

It is broadly old in the art to provide ground-gripping devices for shoes, these having long been used in the form of ice-creepers, 10 golf-cleats, and the like. I make no claim, therefore, to the broad idea of such invention, but only to the improvement which I have added to the art and which will now be described in connection with the drawing 15 forming part of this disclosure.

It will be understood that the drawing of my invention herewith is illustrative and in no sense restrictive, as it illustrates, and the written portion of the disclosure describes, one physical embodiment of my invention, and that best now known to me, which disclosure, however, is subject to such variations and adaptations as are within the range of mechanical skill, without departing 25 from the principle of the invention here involved.

Golf shoes are usually provided with ground-gripping means, such as studs, cleats, rubber made up in various forms and designs, and other devices, to ensure steady footing. Many of these expedients are of special construction and expensive, and, furthermore, do not contemplate, as in the instant case, the utilization of an ordinary, 30 well-fitted, and comfortable shoe for game purposes.

The present development permits the adaptation, for game purposes, of any shoe, and provides means whereby the ordinary walking shoe may be conveniently and quickly converted into a game shoe, and as readily restored to its original condition and purpose. 40

In the drawing herewith, which is described in detail in the accompanying descriptive matter—

Figure 1 is a view of the bottom of a shoe with my invention applied thereto.

Figure 2 is a longitudinal section of a shoe, 50 on substantially the line 2—2 of Figure 1, but

on an enlarged scale, with my invention applied thereto.

Figure 3 is a perspective view looking at the top of my attachment, detached from the shoe.

Referring to the drawing, in which like characters indicate like parts in the several views, A indicates any shoe, having a sole B, to which shoe my invention may be applied.

The device consists of a plurality of plates, 55 two being here shown, each provided with ground-gripping studs or equivalent elements, and each having sole-engaging means. The plates will be contoured and shaped to fit, with reasonable snugness, the bottom of the shoe, and the sole-engaging means will be adapted to clamp the edges of the sole of an ordinary shoe.

This disclosure shows two plates 10 and 11, the plate 10 being disposed at the forward part of the sole and having the clips 12 to engage the sole B. Plate 10 is provided with suitable ground-engaging means, as, for example, studs 13, although it will be understood that any well-known equivalents 70 for the studs 13 may be used, such as cleats, buttons, elastic protuberances, and the like.

Plate 11 will be similarly equipped with sole-engaging clips 14 and studs, so that the ground-engaging surface of the shoe sole will 75 be well-provided with gripping instrumentalities.

It will be observed, however, that plates 10 and 11 are so disposed relative to each other (and this should be observed if more than two plates are employed), that they do not, when applied, interfere with the normal flexibility of the shoe sole B. As here shown, the space between the plates 10 and 11 lies substantially beneath the ball of the 80 foot, where the joints between the foot bones and the toes occur, so that no interference with their flexing can take place. Such an arrangement of a plurality of plates, leaves the shoe, shoe sole, and the foot free to move 85 or flex normally, without the binding or cramping effect of a single plate covering the entire sole.

In the present disclosure it will be noted that the clips 12 on plate 10 and the clips 100

14 on plate 11 are located substantially at the front and rear ends of the plates, respectively, with the clips 12 engaging with a wedging action the tapered toe portion of the sole B, and the clips 14 engaging with a wedging action the reduced portion of the shank of the shoe, so that if the plates are drawn together by suitable means, the clips 12 tend to hug the sole of the shoe tightly, and can only be removed from the shoe by releasing and moving them away from each other so as to shift the front plate off from the toe of the shoe and the rear plate 11 off from the shank of the shoe.

15 In order that the plates 10 and 11 may be held in their adjusted positions, there is provided connecting means between the plates, and, preferably, I provide elastic connecting means which will tend to draw the plates 20 together, and, furthermore, provision is made for adjusting this connecting means so as to put it under more or less tension as the needs of the situation may require.

25 The connecting means is here shown as a strip of rubber 15, one end of which is fastened to the front plate in any suitable manner, as, for example, by the struck-up clip portion 16, here shown as on the front plate, the other end of the strip being secured in any suitable manner to the rear plate, but, preferably, by an adjustable holding means, as, for example, the clamp member 17, which is here shown as a pivoted plate mounted in lugs 18 carried by the plate 11 and provided with a serrated edge to engage the connecting strip 15.

With this arrangement, it will be seen that when the connecting strip 15 is drawn taut and, when it is an elastic strip, put under tension and locked by the clip 17, the plates will be drawn toward each other and held snugly so that their accidental displacement is prevented.

23 Not only does the strip 15 serve as a tensioning means to hold the plates in position, but it may be made of sufficient width to act also as a friction ground-engaging surface which will materially help in giving a firm grip along the central line of the shoe. Being flexible, it will not, of course, interfere in any way with the flexing of the shoe sole between the plates. With the construction shown, the strip 15, if damaged or worn, may be readily renewed by loosening the clip member 16, inserting a new strip, and again clamping the clip member 16 down upon it.

20 While the rubber connecting strip 15 may be variously attached, I prefer the arrangement here shown, where the relatively permanent attachment is on the front plate 10, and provides a flat uninterrupted surface on that plate, with the adjustable clamp 17 at the rear end of the rear plate 11, where, as shown in Figure 2, the clamp 17 is held 65 against the arch of the shoe shank and clear

of the ground line, so that there can be no interference or tripping effect resulting from the clamp 17.

It will be understood that such changes and adaptations as are within the range of mechanical skill may be made in the structure here shown and still be within the purview of my invention.

I claim:

1. An anti-slipping attachment for use with a shoe sole having a tapered toe and tapered shank portion and an intermediate portion of maximum width, said attachment comprising a ground-gripping plate having sole engaging means adjacent its forward end, a second ground-gripping plate having sole engaging means adjacent its rear end, said plates being adapted to be disposed respectively forwardly and rearwardly of said intermediate portion of maximum width of said shoe sole and said sole engaging means being adapted to engage respectively said tapered toe and tapered shank portions of said shoe sole, and a ground-engaging connecting strip of resilient frictional material connecting and underlying portions of said plates and tending to draw them toward each other to draw said sole engaging means firmly into sole engaging position on said tapered toe and tapered shank portions of said shoe sole, said connecting strip being adapted to function as an anti-slipping means in addition to said ground-gripping plates.

2. An anti-slipping attachment for use with a shoe sole having a tapered toe and tapered shank portion and an intermediate portion of maximum width, said attachment comprising a pair of ground gripping plates provided with a pair of clips disposed at the front and rear ends thereof respectively, said clips being adapted to engage the tapered toe and tapered shank portions of said shoe sole respectively, one of said plates being disposed forwardly of said intermediate portion of said shoe sole, and the other of said plates being disposed rearwardly of said intermediate portion, and a ground engaging connecting strip of frictional material spanning said intermediate portion of said shoe sole, connecting and underlying said plates and tending to draw them toward each other to wedge said pairs of clips onto said tapered toe and shank portions respectively, said connecting strip being adapted to function as an anti-slipping means in addition to said ground gripping plates.

3. An anti-slipping attachment for use with a shoe sole having a tapered toe and tapered shank portion and an intermediate portion of maximum width, said attachment comprising a pair of ground gripping plates provided with a pair of clips disposed at the front and rear ends thereof respectively, said clips being adapted to engage the tapered toe and tapered shank portions of said shoe sole

respectively, one of said plates being disposed forwardly of said intermediate portion of said shoe sole, and the other of said plates being disposed rearwardly of said intermediate portion, a ground engaging connecting strip of frictional material spanning said intermediate portion of said shoe sole, connecting and underlying said plates and tending to draw them toward each other to wedge said 5 pairs of clips onto said tapered toe and shank portions respectively, said connecting strip being adapted to function as an anti-slipping means in addition to said ground gripping plates, and means for fixedly attaching said 10 strip to one of said plates and adjustably attaching said strip to said other plate.

4. In an anti-slipping attachment for shoe soles, the combination of two ground-gripping plates, each provided with a pair of 15 clips at opposite ends to engage respectively the tapered toe and tapered shank portions of a shoe sole, a rubber connecting strip secured at one end to the toe engaging plate, and an adjustable clasp on the shank engaging 20 plate to adjustably engage the other end of said rubber connecting strip, said strip underlying portions of said ground-gripping plates and tending to draw them toward each other to wedge said pairs of clips onto said 25 tapered toe and shank portions respectively, said adjustable clasp being disposed at the rear of the shank engaging plate and lying within the arch of the shank and out of normal load supporting engagement with the 30 ground.

In testimony whereof I have hereunto set my hand.

WILLIAM A. BARDEN.
